UNITED STATES PATENT OFFICE.

JOSEPH GIOIOSA, OF EAST MILTON, MASSACHUSETTS.

TORPEDO.

1,406,369.

Specification of Letters Patent. Patented Feb. 14, 1922.

Application filed March 18, 1921. Serial No. 453,412.

To all whom it may concern:

Be it known that I, JOSEPH GIOIOSA, a citizen of the United States, residing at East Milton, in the county of Norfolk and State 5 of Massachusetts, have invented new and useful Improvements in Torpedoes, of which the following is a specification.

This invention relates to improvements in torpedoes.

10 The object of the invention is to provide a torpedo of the type used for fireworks and amusement purposes, said torpedo being so constructed that it will not be easily exploded prematurely during handling or 15 transportation.

Another object of the invention is to increase the strength of the covering of a torpedo over that of articles of this character as previously manufactured and thereby 20 produce an article which in the event of not having been projected against an obstacle with sufficient force to detonate the explosive charge will not break open, thereby scattering said charge and rendering the 25 article inoperative, but which will be sufficiently strong to withstand repeated contact with said obstacle until finally detonated.

Another object of the invention is to render 30 the article reasonably impervious to a moist atmosphere.

Still another object of the invention is to produce a torpedo of the character described having a novel and distinctive contour.

35 The invention consists in the combination and arrangement of parts set forth in the following specification and particularly pointed out in the claims thereof.

Referring to the drawings:

40 Figure 1 represents an elevation of a torpedo embodying my invention.

Fig. 2 is a vertical, longitudinal section taken on the line 2—2, Fig. 1.

Fig. 3 is an elevation illustrating one of 45 the stages of construction of the torpedo.

Fig. 4 is an elevation illustrating another stage of construction of the torpedo.

Like numerals refer to like parts throughout the several views of the drawings.

50 In the drawings, 5 represents a body of material constituting the combination of an explosive charge 6 and a means 7 for detonating said charge intermingled together. The explosive charge 6 is composed of chlo-

55 rate of potash, antimony and sulphur, each in powdered form and mixed together in

suitable proportions. The means 7 for detonating the charge 6 consists of a quantity of small stones, coarse gravel or the like with which a suitable quantity of the explosive 60 charge 6 is mixed as well known to those skilled in the art.

Enclosing the material 5 is a covering consisting of a layer of plain paper 8 of sufficient area to surround said material and 65 allow the edge thereof to be twisted to form an approximately conical shaped portion 9 as illustrated in Figs. 2 and 3. A second layer of paper 10 of slightly larger area than that of the layer 8 and covered upon 70 both sides thereof with a suitable moist adhesive material, as, for example, paste or glue, is placed around the first layer of paper 8 and the edge thereof twisted around the conical portion 9 at 11 as illustrated in 75 Figs. 2 and 4, thereby increasing the size of the conical extension. The layer of paper 10 and the adhesive material thereon is then allowed to dry at which time it will adhere to the layer 8 and the adhesive material will 80 act to stick the folds of the paper together, thereby causing the conical portion 11 to hold its shape.

The article as illustrated in Fig. 4 is then 85 dipped in another suitable adhesive material as, for example, paste or glue, and immediately placed in a receptacle containing fine sawdust or the like, in which it is rolled until thoroughly covered with said sawdust which soon becoming saturated with the 90 adhesive material, forms a plastic covering 12 therearound as illustrated in Figs. 1 and 2. This covering is then allowed to dry, thereby forming a comparatively hard outer surface for the article. 95

If it is desired to have the finished product colored, the article may be dipped in suitable coloring matter and allowed to dry, or the sawdust may be colored prior to being applied as previously described. 100

A torpedo constructed as described is easily and quickly assembled and produces a finished product having a novel and distinctive contour for articles of this character. The outer covering increases somewhat the 105 weight of the article, thereby allowing it to be projected against an obstacle with a greater impact than would be the case if it were eliminated. The outer covering also acts to strengthen the casing enclosing the 110 inner body of material which includes the explosive charge and the means for deto-

nating said charge and produces a torpedo which is safer to handle and less likely to be detonated prematurely.

I claim:

- 5 1. A torpedo embodying therein an explosive charge, means intermingled therewith adapted to detonate said charge, a layer of sheet material enclosing said explosive charge and said detonating means, 10 the edge portion of said sheet material being twisted into a conical shaped projection at one side of said explosive charge and detonating means, a second layer of sheet material covered with an adhesive substance 15 upon both sides thereof and applied to said first mentioned layer of sheet material, the edge portion of said second layer of sheet material being twisted around said conical shaped projection and increasing the size 20 thereof and an outer covering adhering to said outer layer of sheet material and composed of sawdust saturated with an adhesive material.

2. A torpedo embodying therein an explosive charge, means intermingled there-

with adapted to detonate said charge, a layer of sheet material enclosing said explosive charge and said detonating means, the edge portion of said sheet material being twisted into a conical shaped projection at 30 one side of said explosive charge and detonating means, a second layer of sheet material covered with an adhesive substance upon both sides thereof and applied to said first mentioned layer of sheet material, the edge portion of said second layer of sheet material being twisted around said conical shaped projection and increasing the size 35 thereof, a coating of adhesive material covering said outer layer of sheet material and a layer of sawdust adhering to said adhesive material and combining therewith to form a hard outer covering for said torpedo.

In testimony whereof I have hereunto set my hand in presence of two subscribing witnesses.

JOSEPH GIOIOSA.
